Application December 29, 1933, Serial No. 704,411

15 Claims. (Cl. 197—126)

This invention relates to manifolding devices for typewriters, and more particularly, to flat bed typewriters, such as the Elliott-Fisher book typewriter.

5 It is an object of this invention to provide an attachment for typewriters whereby printing may be blocked out of one or more forms in a set of superposed strips. In certain branches of business it is desirable to make an order with 10 duplicate, triplicate or even more copies of a single order for use by the cost, factory, shipping and other departments, and with some of these orders it is preferable that the price, the customer's name and address or other data can be withheld, although it is necessarily included on 15 certain of the other copies in a superposed set. The present invention provides a simple, novel and highly useful arrangement for accomplishing this objective.

20 It is another object of this invention to provide a device, of the character just set forth, which will be moved automatically into the operative blocking out position when a new set of forms is moved into working position relative 25 to the platen, and which may be easily and quickly moved to an inoperative position when it is desired to print on all the superposed forms.

25 A feature of the present invention is the provision of a blocking out sheet which is automatically moved into the operative position with respect to the platen, top worksheet strip and printing mechanism each time a new set of forms in a set of worksheet strips is moved onto the platen. In one form this is accomplished 30 through the provision of a weight on the leading edge of the block out sheet which establishes a gravity bond with the record strip and thereby travels conjointly with this strip into a position overlying the platen.

35 Another feature is the provision of a plurality of blocking out sheets supported by the attachment of the present invention and adapted to be moved into operative position automatically as 40 a set of forms is moved into operative position on the platen and which may be used to block out the data on the original record strip and selected copy strips.

45 And still another feature is the provision of a blocking out sheet which is made of transparent material so that data which are to be typed into the set of forms may be properly aligned with printed sections of the forms even though the facing printed form is not to be typed upon.

50 The device of the present invention may be

used equally well with both roll, straight and flat pack stationery.

5 And yet another feature of the present invention is the provision of a blocking out sheet carrier which is so arranged that a worn or used set of blocking out sheets may be easily and quickly replaced on the carrier with a new and unused set of blocking out sheets.

10 Other features and advantages will herein-after appear.

In the drawings—

15 Figure 1 is a side elevation of a flat platen typewriter with portions of the frame broken away to show, in part, the attachment of the present invention.

20 Fig. 2 is a perspective detail view of the blocking out sheets and carrier of the present invention.

25 Fig. 3 is a perspective view of a pedestal and writing pad of a book typewriter looking at the device from the top and front or operator's side.

30 Fig. 4 is a detail view of the attachment of the present invention, partly in section, applied to the frame of a book style typewriter.

35 Fig. 5 is a detail sectional view of the blocking out device of the present invention in the forward or operative position.

40 Fig. 6 is an enlarged detailed sectional view of the blocking out device of the present invention in the back or inoperative position.

45 Fig. 7 is a detail view similar to Fig. 6, but shows the device in the forward or operative position.

50 Fig. 8 is a perspective view of the work table, and main frame of the present invention.

55 The invention, in its present preferred form, is disclosed as embodied in the well-known Elliott-Fisher book typewriter. It comprises the usual pedestal 12, supporting tracks or rails 13 between which there is mounted a platen 14 on 40 which worksheet strips 15 are supported in interleaved condition with carbon strips 16 to receive type impressions from a printing device 17 movable back and forth and across the platen.

45 In this type of machine the paper strips 15 remain undisturbed on the platen during the writing upon a set of forms 18, said forms having the firm name and other like data usually printed thereon and each strip 15 containing a succession of forms. The spacing between letters 50 and lines is effected by movement of the printing device over the platen. Accordingly, it is only after a set of forms has been written upon and is ready to be severed from the one following that the strips are advanced.

It is within the purview of the present invention to use the blocking out structure with various types of strips; for example, strips in which a transfer medium is carried on the underside of each strip so that a print impression on the top strips is transferred through the transfer medium to the next succeeding lower strips; in which continuous transfer strips are interleaved with the continuous record and copy strips in the now well-known manner; or an arrangement wherein the transfer strips are supported on a play-off reel 19 and take-up reel 20 on opposite sides of the platen 14 and passed transversely between the record and copy strips. This latter arrangement is also well known and is preferably used because it minimizes smudging and is very economical.

It is also within the purview of the present invention to use the blocking out device with various types of strip-feeding and aligning arrangements. For example, it might be used without change in a typewriter providing a pin wheel feed on the marginal edges of the strip. Various types of aligning devices are used in typewriters of this kind to either align a set of forms on the platen 14 or to draw the forms flat and taut thereon. For the purpose of illustration, the structure shown in the present drawings corresponds with the aligning device 21 described in detail in my copending application Serial No. 551,076, filed July 16, 1931. Briefly, it comprises a set of primary or retracting pins 22 on a rotatable cross rod 23 adapted to enter cooperating holes 24 in the paper strips 15 as a set of forms 18 reaches the operative position over the platen 14, and a secondary set of holding pins 25 on the platen adapted to align and limit retractive movement of the strips as the primary pins 22 rotate in a counterclockwise direction as viewed in Figs. 4 and 5 under the influence of a tension spring 26.

Successive sets of forms are, according to the present showing, moved onto the platen by raising the knife edge 27 to the position shown in Fig. 3 through a regular pedal arrangement (not shown) on the pedestal then grasping the set of strips at their leading edge and pulling them forwardly. The secondary pins 25 are slightly hook-shaped and are rounded at the back so that the strips ride thereover when pulled toward the front of the machine and during this pulling movement the primary pins 22 and the rod 23 are rotated in a clockwise direction, as viewed in Figs. 4 and 5, until the then associated holes 24 in the paper strip move free of the pins. As the strips are pulled forwardly approximately one form-length the next succeeding set of apertures 24 are engaged by the primary pins 22 apprising the operator that the lead form is properly advanced over the platen and the operator hooks the lead apertures over the secondary pins 25 while the primary pins, in their rotative movement on the rod 23, align the superposed strips on the platen through the medium of the secondary pins and at the same time draws all the superposed strips taut upon the platen.

Although this aligning arrangement may be built integral with the regular rails 13 of the typewriter, it is, because of its limited application, preferably built as an attachment comprising a frame 28 with side plates 29 spaced and braced by cross rods 30, 31 and 32 and adapted to be fastened to the rails 13 by clamps 33 and to the cross bars 34 and 35 of the typewriter by hooks 34a and 35a.

The attachment frame is provided with a set

of vertical arms 36 for supporting a roll 37 of superposed strips 15 and with a table 38 to support a zig-zag folded pile of superposed strips (not shown) should they be preferred rather than the roll type. A rod 39 in the slot 40 resting upon the roll 37 serves as a brake to prevent excessive unrolling. If zig-zag folded stationery is used the strips are passed from the top of the pile on the table over the cross rod 32 as shown by dot-and-dash lines 41 thence downwardly again around the smaller cross rod 42 and up again below the cross bar 43 and over the primary pin rod 23, the latter path as with the roll type work strips.

The arrangement so far described is in the nature of a standard set-up; viz, an arrangement in which a complete set of forms is given a full set of type impressions. Or, as another example, a set-up in which every type impression on the top sheet is transferred to all the copy forms 20 below. There is no provision in the structure so far described for blocking out certain lines of writing or type impressions on either the top record strip or any one or more of the lower copy strips. Structure for this purpose is the important provision of the present invention. It is about to be described and should, therefore, be noted particularly.

In its present preferred form, the deleting or blocking out structure, provided by the present invention, comprises one or more blocking out sheets 44, adapted to be superposed upon the record strip 15a and interposed upon the copy strips 15b and 15c, as may best be seen in Figs. 3, 6 and 7. Preferably, these blocking out sheets 35 are made of the same width or slightly wider than the worksheet strips and slightly longer than the individual sets of forms. Support and connection of these sheets relative to the attachment is provided through the medium of a cross bar 40 45, made of aluminum or other light weight material, adapted to be passed through sockets 46 or like extensions on the sheets, preferably outside the area of the strips 15 and adapted to ride in a pair of slots 47 in the plates 29. These slots, 45 providing a rim 48 upon which the cross bar rides, may be formed in the rails of the typewriter, but for economy are preferably made integral with the side plates 29 of the removable frame 38 portion of the work strip aligning and supporting 50 attachment. The side rails 13 of the typewriter serve to prevent transverse shifting of the cross bar 45 relative to the attachment plates 29 after the frame 38 is dropped into place between the rails and fastened to the typewriter.

If it is desired to block out type impressions only on the top or record strip 15a the cross bar 45 is provided with only a single block out sheet 44a having at its front end a small weight 49. Loading of the machine with this type of set-up 60 is accomplished by merely pulling the leading set of forms 18, part of the pile of worksheet strips 15, from the roll 37 upwardly and over the primary pin rod 23 then toward the front of the typewriter passing the record strip 15a between 65 the underside of the block out sheet 44a and the cross rod 45 and then over the top transfer strip 16 and the copy strips 15b and 15c between proper transfer strips 16 over the platen 14 until the apertures 24 are hooked over the pins 25. Thus, 70 in loaded condition, the blocking out sheet 44a is only on the top or record strip. As the foremost set of forms is moved onto the platen 14 the weight 49, portion of the blocking out sheet 44a, establishes a frictional bond with the rec- 75

ord strip 15a and travels therewith conjointly into a position overlying the platen and remains in this position while the foremost set of forms is snapped over the hook pins 25 and drawn taut by the primary pins 22 in the manner hereinbefore described.

In use, it is preferable that the operator: first, make the type impressions which it is desired to have appear on the copy strips 15b and 15c but not to have appear on the top record sheet 15a. In this the type impressions are made upon the blocking out sheet 44a rather than on the top record form as the successive lower copy forms 15b and 15c, which have an overlying transfer medium in the form of transfer strips 16, each take the type impression.

After the confidential typing has been made with the blocking out sheet in operative position overlying the platen, according to the present invention, the blocking out sheet may be easily and quickly moved to an inoperative position relative to the forms 18, platen 14 and printing mechanism 17 by merely pushing against the cross bar 45 at one or both sides thereof upon the sockets 46 or by grasping this section of the cross bar and pulling it rearwardly into the position shown substantially in Fig. 6 where the cross bar engages with the back end of the slot 48.

Thereafter, the operator may continue typing, but now in the regular manner; viz, every type impression will appear on the top record form as well as the lower copy forms. After the form has been completely filled, or the necessary entries have been made, the knife bar 27 is raised, the leading edge of the strips 15 is grasped and the set pulled forwardly the equivalent of one form-length until the filled-in forms are clear of the platen and until the next succeeding apertures 24a are hooked over the secondary pins 25 and the strips are aligned and drawn taut by the primary pins 22. The knife edge is seated on the strips again and the typed set of forms are severed from the set of strips along the line of severance 50. As the new set of forms 18 is moved onto the platen 14 the weight 49, through its gravity bond connection with the top record strip 15a, is again pulled forwardly automatically so that the blocking out sheet 44a is on the new working set of forms over the platen, this latter preparation being accomplished entirely automatically and without any conscientious effort upon the part of the operator. The typing operation is then completed in the manner just described.

In some offices and places of use it may be preferable to block out typed data on certain of the copy sheets rather than on the top record sheet. For such cases, the present invention provides a blocking out sheet 44b carried by the cross bar 45 which may be located above the copy sheet on which type impressions are to be blocked out and underlying the transfer strip or medium, which it is desired to render inoperative. For example, if it is desired to delete type impressions on the lowermost copy form 15c the top record strip and first copy strip are passed over the cross bar 45 and the lowermost copy strip 15c is passed underneath the blocking out sheet 44b thence forwardly in proper interleaved position with respect to the transfer strips 16, as may best be seen in Figs. 6 and 7. As the first set of forms are drawn forwardly into the platen 14 a frictional bond, resulting from the weight of the top record strip 15a and first copy strip 15b

resting indirectly upon the blocking out sheet 44b and in effect clamping the sheet between themselves and the bottom copy strip, draws the sheet 44b and cross bar 45 forwardly until movement is stopped by the cross bar engaging the forward ends of the slots 48 in the side plates 29.

Thereafter, the operator types that data which it is desired to have appear on the record strip 15a and first copy strip 15b and not appear on the second copy strip 15c. After such impressions have been made the operator merely pushes or pulls the cross bar 45 into the back or inoperative position where movement is stopped by the back end of the slot 48. The slot and sheet 44b length is proportioned to still permit the front end of the blocking out sheet to remain under the transfer strip 16 in a top area thereof which is not used for type impressions. This latter provision serves to insure travel of the blocking out sheet between the transfer strip and the second copy strip. After the blocking out sheet is moved to the inoperative position the operator may continue with the regular typing in which impressions are made on all three copies.

When the set of forms has been filled with all necessary data, the straight edge 27 is raised, the lead end of the worked set of forms is grasped and pulled one form-length, the next succeeding apertures are aligned with the secondary pins 25 and the filled forms severed along the knife edge. At the same time the untyped set of forms is moved onto the platen 14, the frictional bond of the strip 15c with the blocking out sheet 44b serves to draw the latter downwardly again into the operative position shown in Fig. 7.

In other applications and places of use it may be desired to delete data from both the top record form and one or more of the copy forms and this is accomplished by having both the block out sheets 44a and 44b on the one cross bar 45 as shown in Fig. 2 and by superposing and interposing these respectively in the manner just described in detail. Such an arrangement is clearly shown in Figs. 6 and 7. Although two blocking out sheets are provided, the loading and operation of the blocking out device is just the same as that described hereinbefore for the individual sheets, the only difference might be termed a combination gravity bond connection and frictional bond connection between the blocking out device and the travelling worksheet strips. Although only a single sheet is shown for interpositioning and for blocking out matter on a single copy sheet two or more of such interpositioned sheets 44b may be provided on the one cross bar 45 if it is desired to block out data on two copy strips in a three strip pile or where it is desired to block out data on two or more copy strips of a pile containing several copy strips.

In its preferred form the blocking out structure of the present invention is made as a unitary device comprising a combined main frame 51 and work table 52, as shown in Fig. 8, having downturned ears 53 for connection to the side plates 29 of the aligning device frame 38 or for connection to the side rails 13 of the typewriter with bolts 54. The table is provided with integral turned-up flanges 55 on each side of the table having slots 47a for accommodating the cross bar 45 with the block out sheets 44. Thus, when the combined frame and work table 52 is removed from the typewriter the interconnected

cross bar and blocking out sheet are removed therewith.

As shown in Figs. 4 and 5, a slot connection 41 with the cross bar 45 may be entirely dispensed with by having the cross bar simply ride on the top surface of a table 52a portion of a frame 51a which is like the frame 51 in all respects excepting for the omission of side flanges 55. With this type of structure the cross bar is made just long enough to fit within the side rails of the typewriter if no aligning device is used and just wide enough to slidably fit within the side plates of the aligning device if the latter is used.

It is desirable to align the printing from the mechanism 17 with sections of the top forms 18, like the lines 56 and spaces 51, and, so that this may be done advantageously, the present invention provides the top blocking out sheet 44a to be made of transparent material, linen tracing cloth being very satisfactory for this purpose. The lower blocking out sheets 44b may be made of the same material. The cost of these sheets is so small that a new set of forms may be provided very economically to replace the one set after it contains so much typing that the form below it cannot be made out or be seen clearly. In this replacement it is not necessary to provide a new cross bar 45 or weight 48. Both of these bars are easily and quickly slipped from the used set of sheets into the new unused sheet or set of sheets.

Other variations and modifications may be made within the scope of the invention and portions of the improvements may be used without others.

Having thus described the invention, what is claimed as new and for which it is desired to obtain Letters-Patent, is:—

1. A typewriter having printing mechanism; a platen over which a plurality of worksheet strips are advanced form-length extents to bring a fresh form to writing position thereon; a frame; means for aligning said strips over said platen; means for supporting carbon paper between said worksheet strips; and blocking-out means having a connection with said frame and movable thereon in the direction of travel of the worksheet strips into an operative and in reverse direction into an inoperative position relative to the strips on the platen and the printing mechanism and including a flexible sheet superimposed on the uppermost worksheet strip to prevent writing from being produced anywhere on a form-length thereof when the blocking-out means is in operative position.

2. A typewriter having a platen over which a plurality of record and copy strips are advanced form-length extents to bring a new set of forms to writing position thereon; a frame; means for aligning said strips on the platen; a mechanism for printing on said strips over said platen; blocking-out means having a connection with said frame and movable thereon in the directions of travel of the record and copy strips into an operative position between the record strip and the printing mechanism and to an inoperative position relative to the record strip overlying the platen and to the printing mechanism; and a weight on said blocking-out means resting upon the record strip forming a gravity bond with the strip and thereby effecting conjoint movement of the blocking-out means with the record strip into the writing position on the platen.

3. A typewriter having a platen over which a

plurality of record and copy strips are advanced form-length extents to bring a new set of forms to writing position thereon; a frame; means for aligning said strips on the platen; a mechanism for printing on said strips over said platen; and blocking-out means having a connection with said frame and movable thereon in the directions of travel of the record and copy strips into an operative position overlying one or more copy strips and the platen and to an inoperative position relative to the record strip overlying the platen and to the printing mechanism, said blocking-out means being located between the worksheet strips and forming a frictional bond therewith so as to be drawn into operative position on the platen and under the printing mechanism as a new set of forms is moved into this position.

4. A typewriter having a platen over which a plurality of worksheet strips are advanced form-length extents to bring a fresh form to writing position thereon; a frame; a mechanism for printing on said forms over said platen; a cross bar having a sliding connection with the frame and held to the frame by said connection; and blocking out means having a connection with said cross bar and movable therewith in the directions of travel of the record and copy strips into an operative position and inoperative position relative to the forms on the platen and printing mechanism.

5. A typewriter having a platen over which a plurality of worksheet strips are advanced form-length extents to bring a fresh form to writing position thereon; a frame; a mechanism for printing on said forms over said platen; a cross bar having a sliding connection with the frame and held to the frame by said connection; and a blocking out sheet connected to said cross bar and adapted to be moved therewith in the directions of travel of the record and copy strips into an operative and inoperative position relative to the forms on the platen on the printing mechanism.

6. A typewriter having a platen over which a plurality of worksheet strips are advanced form-length extents to bring a fresh set of forms to writing position thereon; a frame; a mechanism for printing on said forms over said platen; a cross bar having a sliding connection with the frame and held to the frame by said connection; and a plurality of blocking out sheets having a connection with the cross bar, adapted to be so arranged as to be capable of superpositioning upon the top or record strip and interpositioning upon selected copy strips, and movable therewith in the directions of travel of the record and copy strips into an operative position and inoperative position relative to the forms on the platen and to the printing mechanism.

7. A typewriter having a platen over which a plurality of worksheet strips having printed forms thereon are advanced form-length extents to bring a fresh set of forms to writing position thereon; a frame; a mechanism for typing on said forms over said platen; a cross bar having a sliding connection with the frame; and a blocking out sheet connected to said cross bar and adapted to be moved therewith in the directions of travel of the record and copy strips into an operative and inoperative position relative to the forms on the platen on the printing mechanism, said blocking-out sheet being adapted to overlie the uppermost strip and being transparent to disclose therethrough the printed form in typing position.

8. A typewriter having a platen over which a plurality of worksheet strips are advanced form-

- length extents to bring a fresh set of forms to writing position thereon; a frame; a mechanism for printing on said forms over said platen; a cross bar having a sliding connection with the frame; and a plurality of blocking out sheets having a connection with the cross bar, adapted to be superposed on the top or record strip and interposed upon selected copy strips, and movable therewith in the directions of travel of the record 10 and copy strips into an operative position and inoperative position relative to the forms on the platen and to the printing mechanism, automatically moved into the operative position as a new set of forms are so advanced and capable of being moved to the inoperative position without disturbing the forms on the platen.
9. A typewriter having a platen over which a plurality of worksheet strips are advanced form-length extents to bring a fresh set of forms to writing position thereon; a frame; means for printing on said forms over said platen including a transfer medium between said strips; a cross bar, of a greater width than the paper strips, having a sliding connection with the frame; and a plurality of blocking out sheets carried by the cross bar, one of said sheets and the cross bar being interposed between one set of strips, said sheets having a connection with said cross bar at a section thereof in its width beyond the lateral 25 edges of said strips.
10. A typewriter having a platen over which a record strip is advanced form-lengths; a frame; means for connecting said frame to the typewriter; mechanism for printing on said record strip; a blocking-out sheet; a table on said frame; a lightweight bar having a connection with said sheet and supported on said table for movement in the direction of travel of said strip with the sheet toward and from the platen; and a heavy- 30 weight bar also having a connection with said sheet and with the latter resting on the record strip and establishing a gravity bond thereto adapted to pull the sheet and associated lightweight bar into operative position with respect 40 to the platen automatically as the record strip is moved to this position.
11. In a blocking-out device for typewriters, a frame; a plurality of blocking-out sheets; a carrier for said sheets; a guide on said frame supporting said carrier and guiding it in its movement toward and from an operative station; and sockets on said sheets having a sliding connection with said carrier.
12. A typewriter having a platen over which a plurality of worksheet strips are advanced form-length extents; a frame; a printing mechanism; a transfer ribbon between said strips so that a single operation of said printing mechanism writes on all of the forms supported by the platen; means for locking said strips on the platen; a blocking-out sheet between said strips and movable therewith into position on the platen between one of said transfer ribbons and the worksheet beneath it; and means for retracting said sheet from the operative position while the strips 10 remain in locked operative position on the platen.
13. In a blocking-out device for typewriters, a frame; a blocking-out sheet; a carrier bar supported by said frame; a weight bar; and sockets on said blocking-out sheet removably connecting 15 said carrier and weight bars to the sheet.
14. An attachment for typewriters having a frame and a flat platen supported thereby over which a plurality of worksheet strips is advanced form-length extents, said attachment comprising 20 a frame; means for connecting the latter to the typewriter frame at the rear or introductory side of the platen; blocking-out means including blocking-out sheets adapted to be superimposed on worksheet strips supported on the platen; a 25 carrier for said sheets slidably mounted on said attachment frame and movable thereon in the reverse direction to that of travel of the worksheet strips to withdraw the blocking-out sheets from operative position over the platen; and a 30 table on said attachment frame for supporting the blocking out sheets when withdrawn from the platen.
15. An attachment for typewriters having a frame and a flat platen supported thereby over which a plurality of worksheet strips having transversely disposed carbon strips is advanced form-length extents, said attachment comprising 35 a frame; means for connecting the latter to the typewriter frame at the rear or introductory side 40 of the platen; blocking-out means including blocking-out sheets adapted to be disposed between worksheet strips supported on the platen; a carrier for said sheets slidably mounted on said attachment frame and movable thereon in the 45 reverse direction to that of travel of the worksheet strips to withdraw the blocking-out sheets from operative position over the platen; and means on said attachment frame and on said carrier for limiting the withdrawal movement of 50 the carrier and blocking-out sheets so that the edges of the same are not withdrawn beyond the rear edges of the carbon strips.

WILLIAM G. BORCHERS. 55
